UNITED STATES PATENT OFFICE.

EDWARD LINDSLEY AND CHARLES E. LINDSLEY, OF CLEVELAND, OHIO,
ASSIGNORS TO THE LINDSLEY TERMINAL EQUIPMENT COMPANY, OF
ILLINOIS.

TRANSFERRING APPARATUS FOR COAL.

SPECIFICATION forming part of Letters Patent No. 544,103, dated August 6, 1895.

Application filed December 27, 1890. Serial No. 376,159. (No model.)

To all whom it may concern:

Be it known that we, EDWARD LINDSLEY and CHARLES E. LINDSLEY, citizens of the United States, residing at Cleveland, in the county of Cuyahoga and State of Ohio, have invented certain new and useful Improvements in Transferring Apparatus, of which the following is a full, clear, and exact description, that will enable others skilled in the art to which our invention pertains to make and use the same.

Our invention relates to apparatus for transferring coarse bulk material—such as coal, lime, ore, stone, &c.—from one receptacle to another, the discharging-receptacle being at a higher level than the receiving-receptacle. Its object is to transfer material from a higher to a lower level by a system of chutes, conduits, or conductors, in which shall normally be maintained a solid column of the material, the speed or flow of which through the system shall be regulated by suitable appliances to discharge, as desired, and to prevent breakage or disintegration of the material through falling too rapidly from the higher to the lower level, and to reduce the cost or expense of transferring material from one receptacle to another to a lower figure than is possibly attainable by means of any apparatus at present in common use.

It consists of a series of hoppers and chutes, conduits, or conductors with controlling-valves at the lower or discharge end and various appliances or mechanisms to aid in their manipulation, as will hereinafter be fully set forth.

The particular application of our invention shown in the drawings adapts it to transfer material from railway-cars to vessels, the cars being unloaded at an elevation that will admit the employment of a chute reaching horizontally to the center or hatchways of the vessel and have sufficient inclination or natural angle for the material to slide upon. In this particular application the vessel must be loaded from cars on a track at the side; but other forms of vessel than the lake or sea going carrier here illustrated—such, for instance, as canal-boats or flat scows without masts or high upper works—might admit of

the receiving-hopper being placed directly over the vessel and discharging therein through a vertical pipe only, thus dispensing with the inclined chute or other equivalent means of moving the coal horizontally to a point over the vessel.

Our invention is designed chiefly to meet the requirements of the coal-trade, where transhipments from land to water conveyances by present means are slow and expensive, and, owing to the rough handling in the process by which the lumps are cracked or broken and much "slack" created, the coal is greatly lessened in value.

By means of our apparatus we can handle larger quantities of material and do it more expeditiously than has ever before been done, and at the same time by maintaining it in solid column in the conductors can let it down to the discharge-level so gently that no appreciable breakage will occur, no matter how great the fall may be.

Of course the apparatus will advantageously handle other materials than coal, for which it is especially designed, and may be used for other purposes than loading vessels from railway-cars, &c.

In the accompanying drawings we have shown our invention as adapted to the loading of vessels such as are commonly employed in the traffic of the great lakes from railway coal-cars now commonly used by the northern railways of the country in the best form and arrangement of details now known to us for this particular adaptation; but obviously many changes within the skill of a good mechanic might be made in the arrangement of details, and some of the parts used without others, and in relations differing from those shown in the drawings, without departing from the spirit of our invention as set forth in the claims at the end of this specification.

Figure 1 is a plan view, partly in horizontal section, on the lines 11 of Figs. 2 and 3, of portions of a vessel and a dock upon which an apparatus embodying our invention is located. Fig. 2 is a side elevation of the dock and trestle-work supporting our apparatus as seen from the water side. Fig. 3 is a transverse section through the same on the lines 100

33 of Figs. 1 and 2. Fig. 4 is a detail view, on an enlarged scale, of the vertical telescoping end of our conduit or conducting-pipe, partly in section. Fig. 5 is a vertical sectional view on a still larger scale showing the detail of the ball-joints and the controlling worms and sacks of the lower or discharge elbow-sections of the same. Fig. 6 is a general side elevation, partly in section, of the 10 upper or inclined end of the conduit with its carriage and the folding jib upon which it runs in and out, together with the details of the various mechanisms by means of which they are controlled. Fig. 7 is a plan view, and Fig. 8 15 a side elevation, partly in section, on the line 8 of Fig. 7, of one of the jib hinge-joints. Fig. 9 is a side elevation of the same, showing also a transverse section through one side of the jib and carriage with one of the rollers which support the latter on the jib-track. Fig. 10 is a transverse section through one 20 side of the jib and carriage showing the geared neck and pinion for moving the carriage along the jib. Fig. 11 is a vertical transverse section through the jib, carriage, and conduit on the line 11 11 of Fig. 1. Fig. 12 is a transverse section through the conduit-joint on the line 12 12 of Fig. 4. Figs. 13 and 14 are 25 similar sections on the lines 13 13 and 14 14, respectively, of Fig. 4.

We have preferred to show our present improvements as adapted to and working in combination with a car-dumping or transferring apparatus covered by Letters Patent No. 35 418,525, granted to us December 31, 1889. In this apparatus a gondola or coal-car loaded with coal or other material of like nature is run into a cylindrical cage, then raised until the load is brought close to the roof of the 40 cage, when the car is securely clamped in position and the cage rotated on its longitudinal axis, inverting the car and its load. The roof of the cage which then sustains the load is provided with movable shutters, which are 45 withdrawn from beneath the load and allow it to fall into any suitable receptacle placed in position to receive it. This receptacle we originally contemplated was to consist of a series of buckets the aggregate capacity of 50 which should be equal to the capacity of the maximum car, so that the entire car-load would be received at a single discharge. These buckets when filled were to be withdrawn from under the cage and empty ones 55 substituted for them, the filled buckets being taken away and emptied by any suitable means. In loading vessels the filled buckets would be hoisted and swung by cranes or derricks to a position over the hatches of the vessel, 60 where they would be dumped or discharged from the deck into the hold.

The breakage of the lumps of coal due to the long unrestrained fall into the hold and its violent contact with the bottom of the vessel or other coal therein is tremendous, with a consequent deterioration in the value of the coal. Of course the buckets might be, and

sometimes are, lowered through the hatches and their contents dumped gently at the bottom of the vessel or on top of the pile already 70 therein, thus saving the coal from breakage; but this operation consumes so much time that it is almost impracticable and seldom resorted to. Then again we find that our car-dumping apparatus will get the coal out of 75 the cars and into the buckets much more rapidly than the buckets can be removed and replaced by empty ones, and that an enormous number of buckets is necessary to form an equipment equal to the discharging capacity 80 of the dumping apparatus, which it is estimated will discharge a thirty-ton car-load every three or four minutes.

By means of our present improvements we are able to remove the coal from the receiving-hopper of the dumping-machine and transfer it to the hold of a vessel as rapidly as it can be placed in said hopper, and in accomplishing this to handle the coal so gently that it will have no great unimpeded fall and 90 be subjected to no destructive jars or shocks. The car-dumping cylinder or cage A, is mounted on bearing-rolls a, supported by a suitable frame and trestle work A' rising from the dock B at the water side. The track-approaches to this trestle may be by inclines 95 or such other means as may seem best adapted to the circumstances and conditions of each plant.

A stationary hopper C of suitable dimensions to catch the entire load of a car is located immediately beneath the cage A and is suitably attached to and supported by the trestle. This hopper inclines outwardly, as seen in Fig. 3, so that its discharge-mouth c 100 is near the vertical dock-line, and its sides converge as they approach the mouth, so that the hopper is greatly contracted at its lower end. Immediately below this fixed hopper is a movable hopper D, supported by a carriage 105 E, which is arranged to travel in or out on the side rails of jib F, which overhangs the vessel A², as shown in Figs. 1 and 3. The space between the jib-rails f f is entirely clear or free from all obstructions from end to end, so 110 that the hopper D and its attachments may play back and forth between them without hinderance. At the ends they are connected by a cross-bar f' and at suitable intervals along their overhanging portions by yokes f² 115 f², which cross from side to side in a plane above the carriage and have depending legs that are attached to the rails.

The jib may be supported in any suitable manner from the trestle; but we prefer to 120 carry it on a supplementary frame consisting of four posts G, resting upon the trestle or the ground itself, if desired, and connected at their tops by cross-braces and lateral bars with such diagonal or other bracing as may 125 be necessary to give it sufficient rigidity. We prefer to make each of these posts or columns of four angle-irons placed back to back, as shown; but we do not consider any par-

ticular forms or materials of which the parts may be made as essential to our invention. The jib-rails are securely bolted to these columns by suitable brackets, such as G'. (Shown in Figs. 7, 8, and 9.) At a point near the vertical dock-line the jib-rails are hinged at G² to permit the outer overhanging portion of the jib to be folded up against the framework and leave a clear space outside of the vertical plane of the dock-line, so that there may be no projections to become entangled with the standing rigging or other portions of vessels lying at or approaching the dock.

The form of hinge we at present prefer to use at these points is shown in Figs. 6, 7, 8, and 9, in which it will be observed the pivotal center of the hinge is on the line of the tops of the teeth of gear-racks F', located on each rail of the jib, for a purpose presently to be explained. The overhanging end of the jib is supported by guy-rods g, extending from the top of the supplementary frame G, these rods being jointed near their centers to permit of folding of the jib back upon the frame, and provided with turnbuckles to adjust their length to a nicety.

At the back or inside of the trestle and frame the rails f also project a sufficient distance to permit of the carriage being drawn back entirely within the dock-line, and these projecting portions are also trussed by guy-rods g' g² extending from the frame and trestle, as shown. The jib may be raised and folded back upon the frame and trestle by any suitable means. In the drawings we have shown hoisting ropes or cables F², extending from the outer corners of the jib over guide-sheaves g³ g³ on the top of the frame G and down to the winding-drum of a winch G³, located at any convenient and accessible point on the frame or trestle.

The carriage E preferably consists of two side bars, each composed of two longitudinal channel-bars e, placed back to back and sufficiently far apart to permit of the carrying-wheels E' standing between them. These wheels are mounted on axles having their bearings in frame-castings e', secured to the under side of the bars e. The side bars of the carriage are united by cross-bars E², placed at suitable distances apart.

In order to move the carriage we have provided geared racks F' on each rail of the jib and mount a shaft E³ in bearings on the carriage, having pinions e², which gear into the racks. By means of a wheel E⁴ on the shaft it may be revolved by hand direct or through a chain e⁴.

The hopper D at its top extends from one side to the other of the carriage and is of sufficient length to permit of the carriage moving back and forth to any desired extent without the hopper passing from beneath the discharge-opening of the fixed hopper C. By this arrangement the discharge end of the conduit may be moved back and forth in a vessel as far as the length of the hatches a² will per-

mit for the purpose of distributing or trimming the cargo as it is placed in the hold, while the hopper D, being always beneath the hopper C, may be constantly fed therefrom and the operation made continuous.

The sides and back of the hopper slope toward the contracted discharge-throat d at its lower end, and the front slopes back and merges into the throat by an easy curve d', which prevents any tendency of the passing material to clog or choke at this point. From the throat d of the hopper an inclined chute or conduit H extends outwardly as far beyond the dock-line as it may be necessary to move the material to bring it over the point where it is to be finally deposited.

At the point h, near the throat of the hopper, the chute is hinged to permit of its outer end being raised when placed into or withdrawn from the hold of a vessel.

The hinge pivot is placed at the bottom of the chute, so that its lower surface is practically continuous, while the top and sides of the lower section lay outside of those of the upper section, slipping over them when the end of the lower section is raised.

The dividing-line h' between the two sections stands at an angle that will permit the top of the outer section to ride over the inner one, as will be understood from an inspection of the drawings.

At its lower end the chute H connects by an elbow I with a vertical pipe or conductor J, which reaches down into the hold of the vessel to about the level at which the material is finally to be deposited. This pipe consists of several telescoping-sections j j' j'', which admit of adjusting its length when desired.

Upon the elbow are mounted bearing-stands i i, which support a cross-shaft i', having at each of its ends, outside of the bearings, winding-drums i², from which lifting-chains i³ extend to the lower sections j² of the telescopic pipe. A worm-wheel i⁴, keyed on the shaft, is engaged by a screw-worm i⁵ to turn the drums and raise or lower the sections, the shaft i⁶ and hand-crank i⁷ of the worm being within easy access of an operator on the platforms around the elbow. Securely attached to the lower end of the lower section j² is a heavy cast ring K, having formed upon it an annular worm-gear k and ledge k'. Below this lower section is an elbow-joint of pipe L, having at its upper end an annular ring L, which slips over the ring K and embraces the ledge k' thereon by its flange l and abutment l'. This elbow is intended to turn freely on the lower section, so as to point the discharge in any direction, and in order to lessen the friction of the joint and prevent any cramping two rows of antifriction-balls l² are interposed between the ledge k' and the opposing surfaces of the ring L', as clearly shown in Figs. 4 and 5. The ring L' should be made in segments, as many as desired, and bolted together.

A bracket L² mounted on the elbow carries

in suitable bearings a shaft i^3 , upon which is keyed a screw-worm i^4 , meshing into the teeth of the wheel k . This worm locks the elbow in position or revolves it when desired by the operator turning the hand-crank i^5 on the worm-shaft.

The elbow extends through an arc of about sixty degrees, and its discharge-orifice stands at an angle of about thirty degrees, so that it offers no obstruction to the flow of the material, but merely governs the direction of the discharge. In order to control or check the flow we use another elbow M , similar to elbow L , to the lower end of which it is connected by a joint similar to that between the elbow L and lower section j^3 of the telescopic tube.

A heavy cast ring L^3 is secured to the lower end of the elbow L , and has a ledge l^6 , which is embraced by the flange and abutment m^1 of a ring M' , secured to the lower elbow M , rows of balls m^2 being placed at either side of the ledge to lessen friction, as before described. The ring M' has cast upon it a worm-gear rack m^3 , into which a worm m^4 meshes. This worm is keyed onto a shaft m^5 , mounted in suitable bearings in the bracket L^2 on the upper elbow, and is operated by a hand-crank m^6 to turn the elbow M to any desired position. As shown in the drawings, the discharge-orifice of this elbow is pointing down and offering the least obstruction to the flow of material through it.

The direction of the discharge may be governed to some extent and the flow absolutely controlled or checked by this elbow, by revolving it and raising the discharge-orifice to any desired point up to that shown by dotted lines in Fig. 4, where it would be an absolute check to and stop the flow. By means of this elbow we can control the flow without contracting the opening. Other devices—such as valves of various patterns—might advantageously be employed at this point to check the flow, or the lower elbow, or may be both elbows L and M , might be dispensed with and the discharge-orifice of the pipe held in such close proximity to the pile of material which has already passed through it as to sufficiently check the flow and prevent the injurious shock to the material; but at this time we prefer to use the devices shown in the drawings.

In order to raise or lower the outer end of the chute H and the telescopic down-spout attached to it, we employ hoisting ropes or cables N , which extend from the end of the chute to the carriage, and may be wound or drawn up in any desired and convenient manner. In the drawings we have shown them as fastened at one end to the outer end of the carriage and thence passing down to and around guide-sheaves n , loosely mounted on the cross-shaft i' on the elbow I , thence up to and around guide-sheaves n' on a cross-shaft n^2 on the carriage, and thence to the winding-drums o of a winch O , mounted on a platform F^4 , located beneath the outer end of the chute. These drums are mounted on a

shaft o' , carried in bearing-brackets from a base-plate o , attached to the under side of the chute. A bevel-wheel o^2 on the shaft is driven by a pinion o^3 on one end of a shaft o^4 , having at its other end a worm-wheel o^5 , which is driven by a worm o^6 on a shaft o^7 , suitably squared at both ends to receive hand-cranks o^8 , by which it may be turned.

We deem it desirable to hinge the vertical tube to the chute at the meeting-point in order to facilitate getting it into or out of a vessel and possibly also to aid in trimming, the load being deposited therein by swinging the lower end of the vertical tube back and forth independently of the motion of the carriage on the jib-rails. The upper elbow is therefore composed of two segmental sections I and P , the latter being formed on the lower end of the chute H and fitting inside of the section I , which forms the head of the vertical tube J .

The inner section P of the elbow is wider at bottom than it is at top to provide space at each side between it and the outer section for strong cast-metal frames p' , which brace the section firmly and extend far enough below it to be mounted upon the pivot-pin Q , as clearly shown in Figs. 4 and 12. At the top edge of these frames are formed worm-gear racks p^2 , which are engaged by screw-worms mounted on the outer section. The outer section is also provided at each side with strong cast-metal frames R , which are connected by a cross-bar R' beneath the section, this bar being bolted at its ends to flanges on the side frames and provided with depending lugs or standards r' , which are mounted upon the pivot-pin Q . (See Figs. 4 and 12.) Cross-bars R^2 and R^3 also connect the side frames on the outer curve of elbow-section, the upper bar R^3 being formed with bearing-boxes for the shaft i^6 of the telescoping lifting-worm i^3 , and also for two shafts p^3 , which carry the worms P^3 , engaging the racks on the inner elbow-sections. These shafts may each be provided with a hand-crank p^4 , but we prefer to so connect them that they shall work together and act uniformly in drawing the outer section of the elbow over the inner one and thereby swinging the lower end of the vertical tube out of the perpendicular. For this purpose we provide a crank for one shaft only and mount a sprocket-wheel S upon each shaft and connect them by a chain s , so that they will move together. Bevel-gearing and a counter shaft might be employed to effect this purpose and in some instances might be preferred to the sprocket-wheels and chain. Under the arrangement shown the lower tube may be swung either way through an arc of about thirty degrees and held by the worms P^3 in any position.

When the angle of the inclined chute is not very steep, and at points in the conduit where there are turns or changes of direction, it is possible, and it sometimes happens, that the material will become wedged and choke the

chute or conduit and stop the flow therein. These stoppages are most likely to occur, in the apparatus shown in the drawings, at the bottom or throat of the hopper D and at or 5 near the elbow at the top of the vertical tube. To break such a jam and start the material moving again requires a slight agitation, and we have thought of several devices which might be employed for this purpose.

10 One form, shown in Fig. 6 near the throat of the hopper, consists of a shaft T, mounted in bearings beneath the back or lower side of the hopper and provided with one or more fingers T', which play through slots in the 15 bottom of the hopper and lift against the bottom of the mass of material to stir it and disturb the relations of the locking lumps. Normally these fingers lie in the slots with their upper surfaces flush with the bottom of the 20 hopper to keep the slot-opening closed. The shaft may be rocked by any suitable mechanism. We have shown a lever T², mounted on the end of the shaft and standing up near the side of the chute, where it may be reached 25 by a man on the top of the chute.

Another form of agitator is shown mounted on the top of the chute near the elbow, and it consists of a shaft U, having a number of spiders or drag-wheels U' on it, the spurs of 30 these wheels playing through slots in the top of the chute. The spurs are so spaced that one is just about to enter the chute as the other leaves it, so that when at rest none of the spurs stand into the chute to form an obstruction. This drag-wheel shaft is provided 35 at one end with a hand-wheel U', which may be reached by the operator on the winch-platform F⁴, under and extending out from the sides of the chute. Yet another form of agitator is shown beneath the elbow, and consists 40 of a shaft V, mounted in lugs v, depending from the side frames p' of the inner section of elbow. There may be one or more arms V' on this shaft, each connected to a finger or 45 push-bar v', which projects through a hole in the side of the tube. The shaft may be rocked and the fingers forced through the holes and into the clogged mass of material by means of a hand-lever V², attached to the shaft and 50 standing within easy reach of the operator on the platform.

Instead of any of these several devices we might have a simple row of holes in the top of the chute, through any of which a crowbar 55 might be thrust into the packed mass and worked to start it.

The operation of our device will be as follows: In its normal position the carriage E stands in on the rails far enough to have the 60 chute, spouts, &c., entirely within or back of the vertical dock-line, and the jib is folded up against the frame G. A vessel is brought alongside of the dock, with one of its hatches opposite the vertical center of the jib, which 65 is then lowered until it stands horizontally over the hatch. The carriage, with its hopper, chute, and spouts, is then run out on the

jib and the chute and vertical conductor lowered into the vessel to the position shown in Fig. 3, with the exception, however, that the telescopic tube would be drawn up to its shortest length and the lower check-elbow M, with its discharge-orifice, turned up to stop the flow of any material. A car loaded with coal is then run into the cylindrical cage A, where 75 it is raised, clamped, inverted, and the coal dumped, as set forth in our Patent No. 418,525, before referred to, into the stationary hopper C, from whence it runs into the hopper D of the carriage. From this hopper it slides down the 80 inclined chute H and into the vertical pipe J, where it is checked by the elbow M. When the vertical pipe and chute are filled with a solid column of material the lower sections 85 of the vertical pipe are slowly lowered, say, to the position shown in the drawings. Meanwhile other cars in succession are run into the cylinder and dumped as rapidly as possible, and when the chute and vertical pipe are filled the lower elbow is turned to permit the coal to flow out of the lower end, the speed of the flow being regulated so 90 that it about equals the feed of the upper end of the system, and a full column of coal is maintained throughout the system. The 95 movement of this column will be at such a slow rate of speed, comparatively, that the coal will pass down from one level to another in mass and without having been subjected to any such shocks or jars as would tend to 100 fracture the lumps and create slack. The two lower elbows at the discharge end of the pipe may be turned to guide the discharge in any direction at the pleasure of an operator stationed at that point, and the entire carriage, 105 with its hopper, chutes, &c., moved back and forth to distribute and trim the coal as it flows into the vessel. The gradual loading of the vessel causes it to sink deeper and deeper into the water, carrying its bottom away from 110 the lower end of the vertical tube, and this distance may be increased, as desired, by shortening the tube itself. The operator stationed at the upper elbow I may, as directed, raise or lower the tube through the lifting-chains ³, or move the carriage in or out by means of the hand-chain ⁴, passing to the wheel E⁴ on the carriage, or change the angle 115 of the vertical tube by means of the worms P³ and ratchet p² in the upper elbow, or raise 120 the entire apparatus out of the hold of the vessel by means of the winch O and hoisting-ropes N, as before described.

What we claim as new and useful, and desire to secure by Letters Patent, is—

1. In an apparatus for transferring coarse bulk material, a fixed feed hopper having a contracted outlet with a movable hopper beneath it of larger area than the discharge opening of the feed hopper, said movable hopper so constructed and arranged that it may be moved horizontally back and forth through a wide range to trim the material flowing from it yet be continuously fed at any point within

- its range of movement from the fixed hopper, substantially as hereinbefore set forth.
2. In an apparatus for transferring coal or other coarse bulk material, the combination of a fixed hopper and a movable broad mouthed receiving hopper beneath it with a pipe or conduit leading therefrom to a lower level and provided at its lower end with a device to check the flow of material and regulate its speed substantially as hereinbefore set forth.
3. In an apparatus for unloading coarse bulk material from railway cars, the combination of a car dumping device, a receptacle for the material dumped from the cars having a delivery outlet, a movable hopper into which said outlet discharges, the mouth of the hopper being much larger in area than the said delivery outlet; a pipe or conduit leading from the hopper to a lower level, with means at the lower end of the pipe to control and check the flow of material therefrom, all arranged substantially as and for the purpose hereinbefore set forth.
4. The combination of a fixed feed hopper with its delivery outlet, a broad mouthed horizontally movable hopper continuously fed from the fixed hopper at any point within its range of movement, an inclined chute, a vertical pipe dropping from the end of the chute, and means at the lower end of the pipe to control the flow,—substantially as hereinbefore set forth.
5. In an apparatus for transferring coarse bulk material, an inclined chute, and a vertical pipe pivotally connected to the end of the chute, with mechanism for changing and maintaining in any relative position the chute and pipe,—substantially as and for the purpose set forth.
6. The combination of a chute terminating at its lower end in an elbow section, a vertical pipe pivotally connected to the chute and having at its upper end an elbow section that fits over and outside of the elbow on the chute with means for adjusting and holding the two sections in any relative position for the purpose set forth.
7. The combination of a chute and its elbow section, the vertical pipe pivoted to the chute, an elbow on the vertical pipe that fits over the chute elbow, with worm gear racks on the chute elbow and worms on the pipe elbow that take into the racks,—substantially as hereinbefore set forth.
8. The combination of the chute and the elbow section at its lower end, the vertical telescopic pipe having at its upper end an elbow section that fits over the elbow section of the chute, and is pivotally connected to the chute, a shaft with winding drums mounted on bearings on the elbow section of the telescopic pipe with lifting chains extending from said drums to the lower telescopic section of the tube substantially as and for the purpose set forth.
9. The combination of the pipe or conduit and the rotatable elbow at its lower end, the annular ledge or rib K' on the end of the pipe and the ring L' on the elbow, having a ledge at each side of the ledge K' with a row of antifriction balls at each side of the ledge K' substantially as and for the purpose set forth.
10. The combination of a pipe or conduit having an elbow so connected to its end that it may revolve freely, with an annular gear rack on the pipe and the worm on the elbow substantially as and for the purpose set forth.
11. The combination of a fixed feed hopper, a horizontal frame or carriage lying below said feed hopper and supporting a movable receiving hopper, a chute hinged at one end to the receiving hopper and supported at its free end by lifting ropes which pass to the outer end of the carriage frame immediately above it, with suitable mechanism for winding up said ropes to raise the end of the chute substantially as hereinbefore set forth.
12. The combination of a trestle or frame work supporting a railway track and in proximity thereto a hopper having a contracted outlet, a carriage mounted on rails at right angles to and beneath the railway track, a wide-mouthed movable hopper supported on said carriage below the delivery outlet of the fixed hopper and having a chute or conduit depending therefrom, substantially as hereinbefore set forth.
13. The combination of a trestle or frame work supporting a railway track, a pair of track rails at right angles thereto supported on the trestle below the railway track and extending out beyond the side of the trestle in the form of a jib with a movable carriage mounted on the jib rails and a pipe or conduit supported by the carriage and leading to a lower level substantially as hereinbefore set forth.
14. The combination of a frame work or trestle supporting a railway track, a movable carriage supporting a conducting chute or pipe mounted on rails at right angles to and below the railway track said rails extending out on a jib which projects from the side of the trestle frame and hinge-jointed to fold up against the trestle substantially as hereinbefore set forth.
15. The combination of a trestle, the jib hinged to the trestle the track rails and the geared racks extending along the jib and back through the trestle the axis of the hinge pivots being on the line of the tops of the rack teeth with a conduit supporting carriage mounted on the jib rails and the pinions thereon meshing into the rack substantially as hereinbefore set forth.

In testimony whereof we have hereunto set our hands this 22d day of December, 1890.

EDWARD LINDSLEY.
CHARLES E. LINDSLEY.

In presence of—

T. H. GRAHAM,
WM. A. SKINKLE.
